R. McCORMICK.

No Printed Specification Av.

Hemp Brake.

Patented Oct. 1, 1830.

Robert McCormick

Sawmill Patent - Dated October 1, 1820.

The Schedule referred to in these Sawmill Patent and making part of the same containing a description in the words of the said Robert McCormick himself of his improvement in the machine for breaking hemp & flax.

Be it known that Robert McCormick of Stockbridge County State of Virginia have made an improvement in the machine for breaking hemp & flax which is described as follows. This machine consists of the following principle parts 1st The Frame 2nd The bed of bars. 3rd The flat or rocker. 4th The upright posts & top piece. 5th The vibrating bar. 6th The cast iron & lever of the Feeding delivering arms.

1st The Frame is about 24 $\frac{1}{2}$ or 3 feet high about 5 feet long & 6 feet wide & of sufficient strength to support the machinery to be hereafter described.

2nd The Bed of bars. This bed of bars consists of about 8 pieces or less the tops of the 3 in front are made with obtuse planes angles the next 3 are at an acute angle at top & angular at the shoulder. The 3 next are flat at top about 18 $\frac{1}{2}$ or 19 inches with angles at the shoulders. They are disposed in such a way as that when the hemp & flax enters it is slightly crushed, the second set break it still further & the 3rd set complete the operation of breaking. They are made of cast iron 1 $\frac{3}{4}$ inch thick & placed apart at about 2 $\frac{1}{4}$ inches across the frame. This may also be made of wood in the same manner but proportionally strong. 3rd The flat or rocker is made of cast iron & cast whole being a segment of a circle of about 3 $\frac{1}{2}$ feet radius, the flats are made to correspond with the bed of bars before described. It is secured to two rockers made of wood one on each side & the sides are connected by a frame. The ends of the rockers extend beyond the bed of bars about 12 inches. The upright posts & top piece. There are two upright posts about 4 feet high & formed into the rockers one on each side. A top piece connects these posts by being mortised & tenoned into them. 5th The vibrating bar is made of round

Wayslids between the posts across the frame it turns in an zigzag way in the upright post & it has a hole mortised in its middle to admit a bar to the want frame lever. The want frame consists of thin bars of wood one between each two of the bed bars connected together by a piece of wood at each end of the bars. In the frame where the points of the cockers strike are long pins one at each corner, which are sprung down by the motion of the cocker & are attached to the springs below the frame. These springs are very felacious & prop up the want frame by means of other pins near the centre. The want frame is prevented from rising too high by means of steps connected with it & the main frame. There are two bent levers one on each side from which the want frame receives its motion backwards & forwards. These levers are attached to springs that will long enough extend down the frame. The tips of which springs are operated on by a projection attached to the cocker. The feeding & delivering part. These are made similar to those used in threshing machines to receive their motion from a shaft operated on by the lever which work the want frame. Operation. The hump being first properly prepared is laid upon the feeding cloth a sufficient weight is attached to the top & upon the upper part of the flat. to cocker, a bar or driver is put thru' the vibrating bar one end of which may be attached to any machinery that will give it a vibratory motion. Motion being given to the machine the hump is crushed between the flat & cocker & base of bar. the want frame & levers being operated on by the cocker carry forward the hump about 2 inches at each vibration till it is completely broken & delivered upon the side as upon. The cocker is kept in its place by blocks of wood grooved out to receive ends of the cocking frame. What is here claimed as my invention is the whole of the before described machine for breaking humps & for a further illustration of my invention I refer to the model & drawing of the same deposited in the Patent Office. The following that I am giving is a true description of my invention I have subscribed my name before two witnesses at the City of Washington this 3rd day of July 1830.
